I. J. Reynolds,

Buckle,

No 22,454,

Patented Dec. 28, 1858

Inventor:

I. J. Reynolds

UNITED STATES PATENT OFFICE.

UEL. J. REYNOLDS, OF WEBSTER, NEW YORK.

TRACE-FASTENING.

Specification of Letters Patent No. 22,454, dated December 28, 1858.

To all whom it may concern:

Be it known that I, UEL. J. REYNOLDS, of Webster, in the county of Monroe and State of New York, have invented a new and useful Fastener for Attaching Tugs to Harness, called a "Box-Buckle;" and I do hereby declare that the following is a full, clear, and exact description of the construction and operation of the same, reference being had to the annexed drawings, making a part of this specification, in which—

Figure 1 is a perspective view in its connection A face plate E bolt D, edge of plate on the long tug f opposite A, C edge of cap 15 plate on short tug g. Fig. 2, longitudinal view of long and short tugs f and g and plates A, D, C, and bolt E. Fig. 3, a transverse section of the long tug f plates A and D, screws h, h, bolt and spiral spring E, 20 tongue e, sides of thimble c, c, b, large hollow in thimble b small carried through the plate. Fig. 4 transverse section of short tug g, plates B, C, screws i i and eye d, Figs. 5 and 6 is a perspective view of the 25 rear and front of plate D. Fig. 5 the front view of plate D with the thimble c, b the hollow of the thimble and b the hole through the plate. Fig. 6 the rear view of plate D, with the tongue e, and hole b in front end 30 of tongue e, terminating in thimble c. Fig. 7 perspective view of cap plate c, c, its sides ends having holes for screws or rivets. Fig. 8 perspective view of the eye plate B, and the eye d.

35 Description of the construction and operation of the box-buckle.

This buckle is to be made of various sizes and to be of any metallic substance suitable 40 to the purposes for which they are designed the medium or middle size to be made as follows: The plates A, B, C, and D, as shown in Figs. 1, 8, 7, and 5, or 6, to be $1\frac{1}{2}$ inches long 1 inch wide and $\frac{1}{16}$ of an inch in thickness. The face plate A having holes in each corner for screws or rivets and a hole $\frac{1}{4}$ of an inch in diameter $\frac{3}{8}$ of an inch from one end and in center of the sides for a bolt. Fig. 5, front side of plate D, with holes in 45 each corner corresponding with holes in plate A, the thimble C, to be $\frac{1}{2}$ inch long sides $\frac{1}{16}$ of an inch in thickness diameter of hollow b, $\frac{1}{4}$ of an inch depth $\frac{1}{2}$ inch or to the plate with hole b $\frac{1}{16}$ of an inch in diameter and passing through the plate the center corresponding with hole in thimble c.

Fig. 6 rear side of plate D, holes corresponding as seen in Fig. 5, e, the tongue to be $\frac{7}{8}$ of an inch long $\frac{3}{8}$ of an inch wide raised on the plate the rear end being $\frac{1}{4}$ of an inch 60 high and beveled from the back to the front end to a level with the plate D, having in front end the hole b corresponding to the hole in the lower part of thimble c, the sides and back of tongue to be beveled under. 65

The cap plate Fig. 7 has a hole in each end with an oblong opening in center 1 inch long and $\frac{1}{2}$ inch wide, leaving the sides c, c, and ends $\frac{1}{4}$ of an inch wide the front end in front side beveled from inside to outside; 70

Fig. 8 plate B hole in each end the eye d including sides is 1 inch long $\frac{1}{2}$ inch wide sides and ends raised $\frac{1}{4}$ of an inch on the plate B, thickness of sides and rear end $\frac{3}{16}$ of an inch and beveled under the front end 75 is $\frac{1}{8}$ of an inch in thickness the front of the eye d is made wider than the base and of sufficient length and width to receive the tongue e, on plate D, Fig. 6.

The plates A and D, are attached to the 80 front end of the long tug f a hole is cut in the tug to receive the thimble C, the bolt E being passed through the face plate A, the spring is attached and the plate A placed opposite plate D Fig. 5. The spring and bolt 85 E is recessed in the hollow of the thimble C and the two plates with the tug f lying between is put together with screws or rivets.

The eye plate B Fig. 8 is attached to the 90 short tug g numbering 3 or more a hole is cut in the front section of the short tub g of sufficient size to receive the eye d as represented in Fig. 4. Plate B is backed by another section of the tug g and is brought to the section having eye d in it and the cap 95 plate c Fig. 7, is placed over the eye d after it is passed through a section of the tug g. The eye plate B and cap plate c with the tug g lying between is put together with screws or rivets. The rear section of tug g being 100 brought to the front section in which the eyes or eye d is set in the usual way by sticking.

The long tug f is attached to the short tug 105 g as seen in Fig. 1st, by drawing the tongue e, into the eye d, the bolt e raising as the tug f is drawn back falls back of the front end of the eye d, and secures the tongue in the eye the draft on the back end of the tongue e, and against the base of the eye d. The 110 bevel on the tongue and in the eye prevents the tongue from coming out sidewise but in

separating the tugs *f* and *g* the bolt *e* must be drawn out and the long tug *f* carried forward the tug is lengthened by carrying the tug to an eye back of the one in which it is placed and shortened by carrying to an eye forward of the one from which it is drawn.

I do not claim the face plate *A* or bolt and spiral spring *e* as new. But

10 What I do claim as my invention and which I desire to secure by Letters Patent is—

1. I claim the formation of the eye *d*, which receives the tongue *e*, for the purpose above described and set forth.

2. I claim the tongue *e*, in combination with the tube *c*, spiral spring and bolt *E*, which fastens tongue *e*, in the eye *d*, as above described.

15

UEL. J. REYNOLDS.
